UNITED STATES PATENT OFFICE

2,214,988

HOUSE MODEL

Frank Bolhuis, Holland, Mich.

Original application February 25, 1939, Serial No. 258,421. Divided and this application July 7, 1939, Serial No. 283,258

2 Claims. (Cl. 35—16)

The present invention relates to house models, and more particularly to structures adapted for use by architects, contractors, or lumber companies for demonstration and selling purposes.

5 This application is divisional from my copending application Serial No. 258,421, filed February 25, 1939, and is also a continuation in part of my copending application Serial No. 190,385, filed February 14, 1938. This application further relates generally to the subject matter of my Patent

10 No. 2,118,338, issued May 24, 1938.

15 The primary objects of the present invention are to provide such a house model having an improved frame for the reception and retention of interchangeable floor panels and wall panels, said frame being extensible in length and breadth; and, to provide such a structure of simple and economical construction and of especial adaptability for its intended use.

20 An illustrative embodiment of the invention is shown in the accompanying drawing, wherein:

Figure 1 is a perspective view of a partially assembled house model, the roof and certain wall panels being omitted to disclose the skeleton frame of the structure. The particular house model illustrated in the drawing is of extremely simple design and is but one example from a great variety of such models which might be built upon the same frame.

25 Figure 2 is a side elevational view of a corner portion of a two-story skeleton frame.

Referring then to this drawing, the house model there illustrated comprises a skeleton frame generally designated 10, a floor plan panel

30 11, and wall panels 12.

The skeleton frame 10 is supported at the corners thereof by vertically disposed corner posts 13 each having a pair of angularly disposed longitudinal panel receiving slots 14, the oppositely disposed slots of adjacent corner posts 13 being adapted to receive and retain the opposite ends of a wall panel 12 bearing thereon a representation of the wall of a house.

35 Corner members 15 are provided with laterally depending outer side flanges 16 which are secured as by spot welding to the angularly meeting inner surfaces of the corner posts 13 adjacent the upper and lower ends of these posts 13. The several lower corner members 15 form a support

40 for the floor panel 11 removably disposed thereupon and bearing on its upper surface the floor plan of a house.

45 The corner members 15 are each further provided with a pair of laterally depending inner side flanges 17 disposed at right angles to each

other, and a sleeve 18 projects laterally from each flange 17 and is secured thereto as by passing a reduced end portion of the sleeve through an aperture in the flange and riveting over the extreme end of the sleeve.

5 Rods 19 forming the side rails of the skeleton frame have their opposite ends slidably fitted in the sleeves 18 of the corner members 15 secured to adjacent corner posts 13, and set screws 20 threaded in the sleeves 18 provide means for 10 securing the rods in adjusted positions relative to the sleeves. By this arrangement the skeleton frame is rendered extensible in length and breadth to accommodate floor plan panels of different sizes and shapes and wall panels of different widths.

15 In portraying a two story structure, longer corner posts 13¹ are employed as illustrated in Figure 2, and the wall panels used bear representations of the walls of a two story structure. 20 If desired, corner members 15¹ having outer side flanges 16¹ and inner side flanges 17¹ of identical construction as the corner members 15, may be secured to the corner posts 13¹ intermediate the ends thereof, and a second floor plan panel 11¹ 25 may be removably disposed on and supported by said corner members 15¹. It will further be seen that the number of stories in the structure may be increased by using still longer corner posts, appropriate wall panels, and a greater number 30 of floor plan panels and supporting corner members therefor.

35 It will be seen that the representation of windows and doors in the selected wall panels conform to the indications of windows and doors on the selected floor plan, so that upon removal of the roof of the house model, prospective builders may readily form a mental picture of the interior of a proposed house simulated by the house model.

40 While but several specific embodiments of the invention have been herein shown and described, it will be understood that certain details of the constructions shown may be altered or omitted without departing from the spirit of this invention as the same is defined by the following claims.

I claim:

45 1. In a structure of the class described, a skeleton frame comprising vertically disposed corner posts, corner members secured to said posts adjacent the lower ends thereof, side rails longitudinally adjustably connecting the corner posts to render the skeleton frame extensible in length and breadth, and a floor panel removably

supported by the several corner members corresponding in size and shape to the adjusted skeleton frame and bearing on its upper surface the floor plan of a house.

5 2. In a structure of the class described, a skeleton frame comprising vertically disposed corner posts having longitudinal panel receiving slots, corner members secured to said posts adjacent the lower ends thereof, side rails longitudinally adjustably connecting the corner posts to render the skeleton frame extensible in length

and breadth, a floor panel removably supported by the several corner members corresponding in size and shape to the adjusted skeleton frame and bearing on its upper surface the floor plan of a house, and wall panels each having its opposite ends detachably inserted and retained within the oppositely disposed slots of a pair of adjacent corner posts, said wall panels corresponding in width to the adjusted skeleton frame and bearing representations of the walls of a house. 5

FRANK BOLHUIS.
